SAFETY CONTROL FOR GASEOUS FUEL BURNERS

Victor Weber, Greensburg, Pa., assignor to Robertshaw Thermostat Company, Youngwood, Pa., a corporation of Pennsylvania

Application June 25, 1941, Serial No. 399,664

5 Claims. (Cl. 158—117.1)

This invention relates to safety devices for gaseous fuel burners and, more particularly, to safety controls intended to shut off the supply of fuel to a gas appliance, should the pilot burner become accidentally extinguished.

An object of the invention is to cause complete and automatic shut-off of all fuel to both the main and pilot burners when the pilot burner becomes extinguished.

Another object of the invention is to permit fuel to flow to the pilot burner during starting operation while preventing any flow to the main burner.

Another object of the invention is to maintain the pilot burner in continuous operation regardless of whether or not fuel is flowing to the main burner.

Another object of the invention is to utilize positive snap-acting means for accomplishing the shut-off.

Another object of the invention is to arrange the control in compact form as a unitary construction which is adapted for manufacture at low cost and which will occupy the minimum of space when installed in the gas appliance.

Other objects and advantages will become apparent from the following description taken in connection with the accompanying drawing, wherein:

Fig. 1 is a plan view partly in section of the safety control;

Fig. 2 is a longitudinal sectional view through the control;

Fig. 3 is a section taken on the line 3—3 of Fig. 1 looking in the direction indicated by the arrows; and

Fig. 4 is a section taken on the line 4—4 of Fig. 2 looking in the direction indicated by the arrows.

Referring more particularly to the drawing, the control device comprises a housing 10 having an inlet 12 in one side thereof and an outlet 14 substantially perpendicular to the inlet. The inlet 12 and outlet 14 communicate with a chamber 16 extending partly through the housing 10 and terminating in a flat bottom portion 18. The inlet 12 and outlet 14 intersect the chamber 16 intermediate the ends thereof and provide passageways for gaseous fuel to flow therethrough to a main burner connected by any suitable means to the outlet 14. The upper portion of the chamber 16 is threaded for the reception of a cap 20 which serves to close the open end of the chamber 16.

A valve seat member 22 is positioned within

the chamber 16. The valve seat member is generally cylindrical in form, having an upper threaded portion engaging the threaded portion of the chamber 16 below the cap 20, and an unthreaded portion closely fitting within the lower portion of the chamber 16 with its bottom face seated upon the bottom portion 18 of the chamber.

A recess 24 is provided in the bottom face of the valve seat 22 and an annular knife-edge portion 26 projects inwardly thereof to form a seat for a snap disc 28. The snap disc may be of any suitable form and, in this instance, is concavely curved when free. The disc is supported in the recess 24 by a thrust element 30 provided with an annular knife-edge portion 32 similar to the portion 26. In this embodiment the knife-edge 26 is smaller in diameter than the knife-edge 32 and is thus positioned inwardly thereof with respect to the disc 28 to provide the necessary leverage for operation. Both the disc 28 and thrust element 30 have their marginal edges spaced from the walls of the recess 24 providing an annular passage therearound.

The thrust member 30 is loosely supported within the recess 24 and receives an axial thrust from the rod portion 33 of a thermally responsive element 34. The thermally responsive element may be of the rod-and-tube type, and is supported from the housing 10 by the tube portion which threaded engages a projection 36 carried by the housing 10.

The valve seat member 22 is provided with an annular passage 38 extending from the upper end thereof and terminating adjacent the recess 24. A plurality of apertures 40 extend transversely through the wall of the valve seat member 22 intermediate its ends and afford communication between the annular passage 38 and the outlet 14. A second annular passage 42 is formed in the valve seat member 22 within the margin of the other annular passage 38 and substantially concentric therewith. The annular passage 42, however, extends completely through the valve seat member 22 and communicates with the recess 24 being interrupted only by a pair of oppositely disposed webs 43 extending across the lower portion of passage 42 from one wall to the other. Both the outer wall around the annular passage 38 and the inner wall 44 remaining between the two passages are provided with sharp-edged rims. This construction forms a double valve seat comprising an outer portion 36 and an inner portion 40.

A valve member 50 is supported in the chamber

16 for coaction with the double valve seat formed on the valve seat member 22. The supporting and operating means for the valve member 50 comprises a valve stem 52 slidably engaging an axial opening in the valve seat member 22 and carrying a threaded projection 54. The projection 54 engages the snap disc 28 on the side opposite the thrust element 30 and is adjustable with respect thereto due to its threaded engagement with the valve stem. A coil spring 56 extends between the valve member 50 and the underside of the cap 20 and assists the valve member 50 in returning to its seat when the snap disc 28 permits.

Passage of fluid from the chamber 16 to the outlet 14 is controlled by a manually operated valve of any suitable form. In this instance, the valve comprises a tapered plug cock 58 engaging with a tapered seat 60 formed in the housing 10 and having a passage 62 therethrough movable into and out of alignment with the outlet upon rotation of the cock 58 in its seat. The cock 58 is provided with a handle 64 carried on a stem 66 projecting from the cock 58 beyond the housing 10.

The device of this invention not only provides control of the fluid passing through the outlet 14 and thence to the main burner, but also provides control of the passage of fluid to a pilot burner. To this end, a passage 68 is formed in the housing communicating with the chamber 16 above the valve seat member 22. The passage 68 leads to a tapered opening 70 in the housing 10 forming a seat for a pilot shut-off cock 72. The pilot shut-off cock 72 is in the form of a tapered plug having a head projecting from the housing and provided with a handle 74 for manual rotation of the cock in its seat. The cock is retained in its seat by means of a spring plate 76 secured in a recess formed in the cock between the head and the tapered portion thereof and fastened to the housing 10 by a screw 77.

The cock 72 is further provided with an angular passage 78, one end of which is movable into registry with the passage 68 when the cock is rotated in its seat, and the other end of which opens at the smaller end of the tapered portion. An angular passage 80 is formed in the housing 10 and communicates at one end with the passage 78 and at the other end with a pilot control valve chamber 82 also formed in the housing 10.

Adjacent the valve chamber 82 is an enlarged opening 84 extending to the exterior of the housing 10 at the lower end thereof and provided with a threaded portion for the reception of a closure cap 86. The shoulder formed by the junction of the enlarged opening 84 and the valve chamber 82 forms a seat 88 for a pilot control valve member 90. The valve member 90 is provided with a stem 92 extending through the valve chamber 82 and upwardly through a packing chamber 94 formed in the upper portion of the housing 10. The packing chamber 94 is provided with a packing 96 which is compressed into sealing engagement with the stem 92 by means of a spring 98 engaging with the underside of a closure cap 100 threaded into the outer end of the packing chamber 94. A second spring 102 extends between the valve member 90 and the bottom closure cap 86 and serves to maintain the valve member 90 in engagement with its seat 88. The projecting end of the valve stem 92 is provided with a button 104 by means of which the valve member 90 may be moved manually from its seat against the pressure of the spring 102.

A passage 106 extends laterally from the en-

larged opening 84 below the valve seat 88 to a bore 108 within which a pilot adjusting member 110 is rotatably mounted. The upper end of the pilot adjusting member 110 projects into an enlarged portion of the bore 108 at the exterior of the housing 10 and is provided with a slot 112 by means of which the member may be rotated in the bore. The enlargement may be threaded for the reception of a closure cap 114 which is removable for obtaining access to the pilot adjusting member 110 when required. An elongated slot 116 is formed in one side of the pilot adjusting member 110 adjacent the passage 108 and communicating with an opening 118 formed axially in the lower portion of the pilot adjusting member 110. The opening 118 communicates with a lateral passage 120 in the housing 10 leading to a threaded connection 122 for a pilot burner 124. The pilot burner extends from the housing 10 substantially parallel with, and adjacent to, the thermally responsive element 34 so that this element will be heated by the pilot flame.

In order to provide for passage of fluid to the pilot burner 124 when the main valve 50 is open and the pilot control valve 90 is closed, a by-pass is provided in this construction. This by-pass takes the form of an angular passage 126 extending from the bottom portion 18 of the chamber 16 and communicating with the enlarged opening 84 below the pilot control valve member 90. To afford communication between the passage 126 and the main valve chamber 16 around the snap disc 28, the knife-edge seat 26 is provided with a plurality of slots 128 through which the fluid may pass.

The operation of the device is as follows: In starting the appliance to which the control is attached the gas cock 58 controlling the outlet 14 should be in closed position. Under such conditions and assuming that the thermally responsive element is not operating, the valve 50 will also be closed due to the normal or concave position of the snap disc 28. The valve 50 being in closed position no fluid from the chamber 16 can pass through the by-pass to the pilot burner 124 and the pilot control valve 90 being normally closed also prevents fluid from passing to this pilot burner. Additional safety is provided by the provision of the pilot shut-off cock 72 which may also be in closed position at this time.

The appliance is started by first manually depressing the pilot control valve 90 by means of the push-button 104 permitting fluid to pass from the valve chamber 16 by way of passages 68, 80, 55 and 106 to the pilot adjustment member 110. This member is normally left in adjusted position and the fluid may pass through the slot 116 therein and out of the opening 118 to enter the passage 120 which communicates with the pilot burner 124. The pilot burner is then lighted and causes operation of the thermally responsive element 34 in the usual manner to create a thrust against the thrust plate 30 moving it away from bottom portion 18 and operating the snap disc 28 to the convex position as shown in the drawing. By means of the projection 54 described, the movement of the snap disc 28 causes movement of the valve member 50 from its double seat exposing both annular passages 38 and 42. The fluid in the valve chamber 16 may then flow by way of annular passage 38 and apertures 40 to the outlet 14. If not previously opened, the main gas cock 58 may then be rotated to open position and the fluid will pass to the main burner which may then be lighted.

Upon moving the main gas cock 58 to open position and after the snap disc moves to convex position the manual pressure on the push-button 104 may be released, thus permitting the pilot control valve 90 to close. Such closing of the pilot control valve 90 will not shut off all flow of fuel to the pilot burner 124 due to the provision of the by-pass arrangement. It will be apparent that as soon as the valve member 50 is moved off its seat by the snap disc 28 the fluid from the valve chamber 16 may pass through the annular passage 42 around the snap disc through the grooves 128 to the passage 126. The fluid then travels through the enlarged opening 84 below the pilot control valve 90 to the passage 106 and flows through this passage by its ordinary path to the pilot burner. The safety control is then in complete operation.

Should the pilot flame, for any reason, be extinguished the thermally responsive element will cool and the snap disc 28 will reverse to its concave position permitting spring 56 to close the main valve 50. When the main valve 50 closes, the passage of fluid to the main burner by way of outlet 14 is cut off and also the passage of fluid to the pilot burner by way of the by-pass. Thus, a complete and automatic shut-off of all fuel to both the main and pilot burners occurs whenever the pilot burner becomes extinguished. The concentric annular passages 38 and 42 permit the use of a single valve 50 which controls the passage of fluid to both the main and the pilot burners when the control is in operation. Moreover, means have been provided to control the flow of fuel to the pilot burner individually when starting the appliance and to change over to the running position wherein this burner is controlled by the valve controlling the main burner also.

I claim:

1. A safety control for gaseous fuel burners comprising, in combination, a housing having a chamber therein, inlet and outlet openings communicating with said chamber and providing a passage for fuel to a main fuel burner, a valve seat member positioned in said chamber, a main valve member cooperating with said seat for controlling the passage of fuel from the inlet to the main fuel burner, an auxiliary valve in said housing for controlling the passage of fuel from said inlet to a pilot burner, means biasing said auxiliary valve to closed position, thermo-responsive means positioned to be acted on by a flame from the pilot burner, actuating means for opening and closing said main valve member including valve opening means operable by said thermo-responsive means, manually actuatable means for initially opening said auxiliary valve, said biasing means causing return of said auxiliary valve to normally closed position upon release of said manual means when said actuating means has opened the main valve, and a by-pass for said auxiliary valve communicating with said valve seat member, said by-pass being under common control with the main fuel passage by said main valve member for maintaining a flow of fuel to said pilot burner when the auxiliary valve is closed and the main valve open.

2. In a valve, a housing having a chamber therein, inlet and outlet openings communicating with said chamber and providing a fluid passage, a valve seat in said chamber having a pair of annular passages therein substantially concentric one with the other, one of said passages com-

municating with both the inlet and outlet openings and the other with the inlet only, a by-pass communicating with the last said passage for diverting fluid from the outlet opening, a valve member coacting with said seat and biased into engagement therewith for closing both passages from the inlet opening, and actuating means for said valve member occupying part of said by-pass.

3. In a valve, a housing having a chamber therein, inlet and outlet openings communicating with said chamber and providing a fluid passage, a valve seat in said chamber having a pair of annular passages therein substantially concentric one with the other, one of said passages communicating with both the inlet and outlet passages and the other with the inlet only, a by-pass communicating with the last said passage for diverting fluid from the outlet opening, a valve member coacting with said seat for closing both passages from the inlet opening, a valve stem connected to said valve member and projecting through said seat, and actuating means for said valve stem carried by the housing.

4. In a valve, a housing having a chamber therein, inlet and outlet openings communicating with said chamber and providing a fluid passage, a valve seat in said chamber having a pair of annular passages one within the other and substantially concentric, the inner and outer walls of said passages terminating in a double seat, one of said passages communicating with both the inlet and the outlet passages and the other with the inlet only, a by-pass communicating with the last said passage for diverting fluid from the outlet opening, a valve member coacting with said seat for closing both passages from the inlet opening, a spring urging the valve member into engagement with said seat, a valve stem connected to said valve member and projecting through an aperture in said seat interiorly of the said annular passages therein, a snap disc engaging said valve stem and acting in opposition to said spring to move said valve member away from said seat, said disc being spaced from said housing to provide passage for fluid through said by-pass, and means carried by said housing for actuating said disc.

5. A safety control for gaseous fuel burners comprising, in combination, a housing having a chamber therein, inlet and outlet openings communicating with said chamber and providing a passage for fuel to a main burner, a valve seat in said chamber having a plurality of passages therein, at least one of said passages communicating with the inlet and outlet openings, a main valve member coacting with said seat for closing said valve seat passages from the inlet opening, an auxiliary valve in said housing, a passage leading from the inlet side of said chamber to said auxiliary valve, a passage leading from said auxiliary valve to a pilot burner, actuating means for said auxiliary valve for controlling the flow of fuel between said inlet passage and said pilot burner, thermo-responsive means positioned to be acted upon by a flame from the pilot burner, actuating means for said main valve member operable by said thermo-responsive means, and a by-pass communicating with the outlet side of said chamber for maintaining a flow of fuel to said pilot burner when the auxiliary valve is closed and the main valve open.

VICTOR WEBER.
